9 Claims. (Cl. 178—4.1)

This invention relates to telegraph station selectors and more particularly to station selectors incorporated as components at each station of a multistation system whereby selective intercommunication over a common signaling channel may be obtained between various arrangements of the stations.

Many telegraph systems have been devised to provide for the selective intercommunication of a transmitting station with varying numbers of receiving stations. These systems can in general be placed in two broad categories; namely, those systems wherein all or a number of the stations can be interconnected through the agency of a switching center and those systems wherein each station is permanently held in operative association with a single communication channel, but where certain of the stations can be rendered nonresponsive to the recordation of subsequently transmitted messages. The present invention relates to the latter of these systems which in general depend for operation upon the utilization of electromagnetic relay or mechanical time delay devices for the selection of stations to record transmitted messages. The use of electromagnetic relays as time delay devices presents serious complications when such relays are incorporated as line relays because the inductance of these relays must be held at a minimum, otherwise detrimental inductance is introduced into the transmission line. When consideration is given to the factor that inductance must be held to a minimum and that the time of delay is of critical significance then it is apparent that existing electromechanical time delay devices provide only marginal delays and after a period of time the delay attained with these devices is unpredictable.

Usually when time delay relays are incorporated into a transmission line, the actuation of the outlying receiving stations is attained by a prolonged break in the transmission line; consequently, it may be appreciated that when these systems are transmitting at relatively slow speeds the impression of a signal indicative of a blank will provide a break in the transmission line of sufficient duration to trip the station selecting devices at all the outlying stations, thus rendering all the stations responsive to the subsequently transmitted portions of the message.

A primary object of this invention is to provide telegraph station selectors utilizing simple, economical and dependable components.

In adjunct with the first object it is a further object to provide a station selector devoid of any marginal electromagnetic or mechanical time delay devices.

A further and more finite object of the invention resides in the provision of telegraph station selectors utilizing electronic timing devices having improved operating margins.

Another object of the invention resides in station selectors having readily adjustable time delay devices adapted to be actuated by a variety of different multielement codes or upon application of signals transmitted at different transmitting speeds.

2

The present invention is described in relation to a printing telegraph apparatus of the type shown in the patent to S. Morton et al., No. 1,904,164, dated April 18, 1933, wherein selectively operated mechanisms are shown as being capable of closing switches in response to the receipt of preconcerted telegraph signals. It is to be understood, however, that the present invention is not restricted to an incorporation in such a printing telegraph apparatus, but rather is readily adaptable to operate in conjunction with many other diverse types of telegraph transmitting and receiving equipment.

With these and other objects in view the present invention contemplates a multistation telegraph communication system permanently interconnected by a single communication channel and having facilities therein whereby each station of the system can initiate a call to any other station in the system. Initiation of a call is attained by opening the signaling channel to all the other stations for a time interval determined by the operation of an electronic timing device, whereby electronic timing circuits at all the outlying stations are actuated to start motors for driving the associated printing telegraph apparatus.

Facilities are provided at each station so that when a station initiates a call to the other stations the normally quiescent motor at this station is immediately placed in operating condition. Thereafter the calling station transmits a series of signals indicative of the calling stations and the stations designated to receive the message. The transmission of this series of signals actuates locking circuits at the calling station and the designated receiving stations to hold the motors thereat in a running condition. In addition the receipt of the calling signals at designated stations initiate the operation of instrumentalities to transmit back to the calling station an answer back signal thereby informing the calling station that the designated receiving stations have their respective motors in a locked running condition.

Subsequent to the transmission of the call signals, signals indicative of a disconnect function are transmitted over the communication channel to de-energize the motor control circuits at the stations which have not been locked and are not to receive the message. Obviously since the printing telegraph apparatuses at the nonselected stations have their motors placed in a quiescent state these stations will not cause the recordation of the subsequently transmitted messages.

In order to restore all the stations to an idle condition following transmission of a message, preparatory to the transmission of messages to other groups of stations, the electronic timing circuit at the initiating circuit is again operated whereupon the transmission channel is again interrupted for a prolonged period of time to energize the time delay circuits at the unoperated stations whereupon the motors thereat commence to rotate. The time delay circuits at the previously operated stations are also energized to disrupt the locking circuits for their respective motors, but these motors are held operative by an auxiliary locking circuit having included therein a contact adapted to be opened by the receipt of a special disconnect signal from transmitting or calling station. When the disconnect signal is transmitted over the communication channel, motors at all the outlying stations are brought to rest and in addition the locking circuit for the motor at the transmitting station is likewise disrupted to bring the motor thereat to a stop. The system is thus placed in an unoperative condition preparatory to the transmission of subsequent messages to other combinations of stations.

Other objects and advantages of the invention will be apparent from the following detailed description when considered in conjunction with the accompanying drawing wherein:

Fig. 1 discloses a telegraph communication system embodying the principal features of the invention and more particularly the specific circuits employed at two of the stations together with the mechanical elements for controlling said circuits.

Referring to the drawing, there are shown two stations 10 and 11 each of which has identical circuitry. Two other stations 12 and 13 are also shown in block diagram form; but, it is to be understood that the circuitry included in these stations is identical to that shown in stations 10 and 11. It is to be noted that all the stations 10, 11, 12 and 13, are interconnected by a common communication channel which in this instance is represented by a transmission line designated by the reference numeral 14.

Each of the stations is provided with a printing telegraph apparatus of the type shown in the afore-identified patent to S. Morten et al., having selector magnets 16 which are permanently associated with the transmission line 14. Each printing telegraph apparatus has a keyboard transmitter whose contacts are designated in this instance by the reference numeral 17. At station 10 one of the key levers representative of the letter A is shown and denoted by the reference numeral 18. A key lever representative of the printing telegraph apparatus at the station 11 is designated by the reference numeral 19. It is understood from the Morton et al. patent that the depression of the key levers 18 and 19 results in the permutative position of a number of code bars 21 to control the keyboard contacts 17 to impress start-stop signals of the Baudot code on the transmission line 14.

Further, each printing telegraph apparatus at the respective stations is provided with function levers 22, 23, 24 and 25 of the type shown in Fig. 6 in the Morton et al. patent and designated by the reference numeral 175. In the present invention the function levers 22 are adapted to be actuated by the receipt of a signal indicative of a space function whereas the function levers 23 are adapted to be operated in accordance with the receipt of a signal representative of a carriage return function. Function lever 24 is adapted to be operated in accordance with a letter code signal which is representative of the identification of the station denoted by the reference numeral 10 whereas the function lever 25 is adapted to be operated in accordance with the receipt of a signal at the station 11 which is representative of the letter code signal of that station. Each of the stations is also provided with a motor 27 for driving the printing telegraph apparatus thereof and as illustrated in the drawing when the stations are in the idle condition the motor circuits are open at contacts 28.

For purposes of illustration assume that circuits at each station 10, 11, 12 and 13 are in the idle condition which condition is illustrated in the drawing. When it is desired to initiate a call from a station such as station 10 to station 11 the operator at station 10 momentarily depresses a start push button 31. Closure of push button 31 applies positive battery through a normally unoperated contact 32 of a relay 33, through a fixed contact 34, to an unoperated contact 35 of a relay 36, over a lead 37, through an unoperated contact 38 of a relay 39, through a fixed upper contact 45, through the now closed push button 31, through a left-hand coil of a relay 40 to negative battery. Energization of the left-hand coil of relay 40 completes a locking circuit which may be traced from positive battery through the now drawn up contact 41 of the relay 40, through the left-hand coil of relay 40 to negative battery. In operating, relay 40 breaks the transmission line 14 at a now opened contact 42 causing a low inductance line relay 43 to assume a state of de-energization thereby causing a contact 44 associated therewith to move from its lower to upper contact.

Prior to the operation of push button 31 a charging circuit existed from positive battery through the relay 33, through a contact 46, through unoperated contacts 47 and 48 of the relay 40, through a high resistance 49 to a junction point 50, however, no charge was accumulated on a condenser 51 due to the fact that junction point 50 was connected through the normally drawn up contact 44 to negative battery. It is to be appreciated that the relay 43 follows the energization of the transmission line 14 in accordance with signals impressed thereon to release the contact 44 each time the transmission line 14 is interrupted by a spacing signal impulse. Release of contact 44 thereupon permits a charge to be impressed through junction point 50 to the plate of the condenser 51, however, the R. C. value of this circuit is such that insufficient charge is accumulated to raise the potential at the junction point 50 a sufficient amount so that the voltage impressed on the starter anode of the cold cathode tube 52 is sufficient to fire this tube. The voltage at junction joint 50 and on the starter anode does not rise to sufficient voltage because the line relay 43 is again energized by a marking or current impulse to move the contact 44 into engagement with its lower contact to discharge the condenser 51.

The value of resistance 49 and capacitance 51 should be selected so that the tube 52 will not be fired during the normal transmission of any signals over the transmission line 14, but only upon the occurrence of a prolonged break in the transmission line which is greater than the time occupied for the transmission of any signal over the line. The resistance 49 is made adjustable in order that the charging circuit may be responsive to various time breaks in the transmission line 14, which may occur due to the change in number of code impulses comprising a signal or as a result in a change in the transmission speed of the signals impressed on the line 14.

When the left-hand coil of the relay 40 operates to open the transmission line 14 the contact 42 thereby releases the relay 43 to cause the contact 44 to move from engagement with its lower contact and the discharge circuit previously traced is interrupted. Closure of the contact 41 associated with the left-hand coil of the relay 40 also completes an auxiliary charging circuit for the condenser 51 which may be traced from positive battery through the contact 41, through the right-hand coils of the relay 40, through a varistor 54, through a resistance 55, through the resistance 49 to the junction point 50 to the condenser 51. The values of resistance 49 and 55 are rather high, hence the charge built up at junction point 50 is not immediately of sufficient value to fire the cold cathode tube 52.

During the time that the charge is building up at the junction point 50 the contact 44 is positioned in engagement with its upper contact to complete an energizing circuit for the relay 33 which may be traced from positive battery through the windings of the relay 33, through the contact 46, through the now drawn up contact 47 of the relay 40, over a lead 56, through the now released contact 44 of the relay 43 to negative battery. Energization of the relay 33 completes a locking circuit which may be traced from positive battery through the windings of the relay 33, through a now drawn up contact 57, over the lead 56, through the released contact 44 of relay 43 to negative battery.

Energization of the relay 33 also draws up the contact 32 into engagement with a stationary contact 58 to complete an energizing circuit for a relay 59 which may be traced from positive battery through the now closed contacts 32 and 58 of the relay 33, over a lead 61 and thence to the windings of the relay 59 to negative battery. Energization of the relay 59 completes a locking circuit therefor which may be traced from positive battery through a normally closed contact 62 associated with

the function lever 23, through a normally closed contact 63 associated with the function lever 22, over a lead 64, through a now drawn up contact 66 of the relay 59 through winding of relay 59 to negative battery. Closure of the contact 66 having positive battery thereon, also completes a circuit to operate an indicating lamp 67 which apprises the operator at this station that his printing telegraph apparatus is in running condition. Energization of the relay 59 simultaneously effectuates the closure of the contact 28 to complete the energizing circuit for the motor 27 of the printing telegraph apparatus located at station 10.

After a period of time sufficient charge is accumulated on the condenser 51 to raise the potential at junction point 50 to a value sufficient to cause the potential on the starter anode of the tube 52 to rise to a value whereby the tube 52 is placed in a conductive state. When the tube 52 commences to conduct, a circuit is completed from positive battery through the drawn up contact 41 of the relay 40 through the right-hand windings of the relay 40, through the varistor 54 to the anode of the tube 52 and hence to the cathode of this tube which is connected to negative battery. When tube 52 commences to conduct, current flows through the right-hand windings of the relay 40 to set up a magnetic field which nullifies the effect of the previously energized left-hand windings of relay 40; thus relay 40 will release all of its associated contacts 41, 42, 47, and 48. Upon release of the contact 42, the transmission line is again closed to apply normal energizing current over this line to again re-energize the relay 43. Energization of the relay 43 moves the contact 44 from its stationary upper contact thereby disrupting the previously traced locking circuit for the relay 33. Of course, the release of the contact 41 of the relay 40 removes positive potential from the anode of the tube 52 thereby causing this tube to again assume a nonconductive condition.

Considering now the events that occur at all the other receiving stations 11, 12 and 13 when the contact 42 contained in the transmission line 14 at station 10 is opened for a prolonged period of time, it will be noticed that the line relays 43 at all the stations will be de-energized. Considering station 11 as a typical outlying receiving station the de-energization of the relay 43 causes the contact 44 thereof to move from engagement with its lower stationary contact into engagement with its upper stationary contact. As previously indicated with respect to circuits shown at station 10 a charging circuit for the tube 52 exists which is traced from positive battery through the windings of relay 33, through the normally closed contact 46, through the unoperated contacts 47 and 48, through the resistance 49 to the junction point 50. When the contact 44 moves into engagement with its upper contact negative battery which was applied to junction point 50 is removed whereupon the condenser 51 at this station commences to accumulate a charge and which after a relatively small period of time, as determined by the value of the resistance 49 and the capacitance value of the condenser 51 raises the potential of the junction point 50 and hence of the start anode of the tube 42 to sufficient magnitude to cause this tube to commence conduction and thereby establish an energizing circuit for the tube which may be traced from positive battery through the windings of the relay 33 through the normally closed contact 46 of the relay 33, through the normally unoperated contact 47 of the relay 40, through the tube 52 to negative battery.

Energization of the relay 33 follows, and the make before break contact 57 is drawn up to establish a locking circuit for the relay 33 which may be traced from positive battery through the windings of relay 33 through the now drawn up contact 57 through the withdrawn contact 44 of the de-energized line relay 43 to negative battery. Energization of the relay 33 also opens the

contacts 46 to withdraw the source of positive battery from the anode of the tube 52 thereby restoring this tube to its normal nonconductive state. Energization of the relay 33 also draws up its movable contact 32 into engagement with the fixed contact 58 to again complete an energizing circuit for the motor control relay 59 located in this station. Energization of the relay 59 draws up its contact 28 to complete an energizing circuit for the motor 27 and simultaneously therewith the contact 10 66 closes to complete a locking circuit for the relay 59 which may be traced from positive battery through the contacts 62 and 63 located at station 11 over the lead 64 through the now drawn up contacts 66 of the relay 59 and from there through the windings of the relay to negative battery. Again an indicating lamp 67 at this station is also operated upon closure of the contact 66. When the line contact 42 at the calling station 10 is again closed as previously described, the line relays 43 at the calling station and all the outlying stations are also re-energized moving the associated contacts 44 back into engagement with the lower contacts. Upon this move of the contacts 44, the source of negative battery for the locking circuits for the relays 33 are removed, consequently these relays are de-energized to assume the normal unoperative conditions as shown in the drawings. The system is now in such a condition that the motors 27 at each of the stations 10, 11, 12, and 13 are in running condition and the printing telegraph apparatus at each of these stations is in condition to perform functions or record indicia in accordance with the signals impressed on the transmission line 14.

Now the initiating operator at station 10 depresses a key lever in his printing telegraph apparatus which is indicative of the letter A, hence causing a movement of the function lever 24 to close a contact 71. Actuation of the key lever representative of an A signal causes a recording of the letter A at the initiating station and at all the outlying receiving stations. Closure of the contact 71 completes an energizing circuit for the relay 36 which may be traced from positive battery through the now closed contact 71, through normally closed contacts 72 of the de-energized relay 39, through contacts 73, through the windings of the relay 36 to negative battery. Energization of the relay 36 completes a locking circuit therefor which may be traced from positive battery through the pair of now closed contacts 32-34 of relay 33, through a now closed pair of make before break contacts 74, through the windings of the relay 36 to negative battery. Closure of the contacts associated with the relay 36 also completes an auxiliary locking circuit for the motor control relay 59 which may be traced from positive battery through a pair of now closed contacts 76 of the relay 56, over the lead 64 through the now closed contacts 66 and finally through the windings 55 of the motor control relay 59 to negative battery. Closure of this auxiliary locking circuit for the motor control relay 59 permits the initiating station to respond to all subsequently transmitted signals over the transmission line.

When the call contacts 71 were closed, an additional circuit was completed to an answer back magnet 78 which is traceable from positive battery through the now closed contact 71 through the normally closed contacts 72 of the relay 39 and through the windings of the magnet 78 to negative battery. Energization of the magnet 78 causes its armature to be drawn up and a mechanism attached thereto causes the answer back key lever 18 to be operated thereby actuating a recordation at the initiating station and all the outlying stations of a signal indicative of the operation of the answer back key lever.

When the relay 36 at station 10 operates, its contact 35 closes to impress positive battery through the normally closed contact pairs 32-34 over the now closed contacts 35 over a lead 79, over a lead 81 through the windings of the relay 39, through a junction point 82

through a resistance to negative battery. However, the relay 39 is not operated at this time due to the fact that the closure of the contacts 71 impresses positive battery through the normally closed contacts 72, through a resistor 83 to the junction point 82. Inasmuch as this circuit impresses a positive potential at the junction point 82 this circuit in effect acts as a short circuit for the relay 39 and precludes its operation until such time as the contacts 71 open. Contacts 71 will open following a recordation of the A signal at the station 10 whereupon the shunt circuit to junction point 82 is opened thereby permitting the relay 39 to now operate. Operation of the relay 39 draws up a contact 84 to complete an energizing circuit for a busy lamp 86 which may be traced from positive battery through the normally closed contact pair 32-34 of the relay 33 over the lead 37, through the drawn up contacts 84 of the relay 39, through the busy lamp 86 to negative battery.

The operator at station 10 now sends call characters which are indicative of the stations desired to receive the forthcoming message. The transmission of a signal representative of the letter B which is also the call letter for the station 11 causes a recordation of the letter B at all of the stations in the system. Receipt of a signal indicative of the letter B at the station 11 causes the function lever 25 to close the contacts 71 thereat. As described in relation to the operation of the circuits at the station 10, closure of the contacts 71 effectuates an operation of the relay 36 to complete an auxiliary holding circuit for the motor control relay 59 located at this station. Closure of the contact 71 also effectuates an operation of the answer back magnet 78 located at this station which operation causes the key lever 19 to be operated thereby causing this station to transmit a signal representative of the answer back designation of this station. This signal again is recorded at all of the stations in the system. When the contacts 71 at station 11 open following recordation of the call letter, the relay 39 at this station operates to effect an illumination of the busy lamp 86.

The operator at station 10 now transmits a signal indicative of the space function which action causes an operation of the function lever 22 to move the contact 63 from engagement with the upper stationary contact to an engagement with the lower stationary contact. This operation also occurs at all of the outlying stations in the system whereupon those stations, whose relays 36 have not been operated to complete the auxiliary locking circuits, are placed in the unoperated condition by having the locking circuits for the motor control relays 59 interrupted at contacts 63 thereby releasing the energizing circuits for the motors 27 at each of these stations. It may be thus appreciated that the stations with the de-energized motors will not effect a recording of the subsequently transmitted messages.

At the unoperated stations the movement of the contact 63 into engagement with the lower stationary contact completes a circuit which may be traced from positive battery through the normally closed contacts 62, through lower contacts 63, through the windings of the relay 39 to negative battery, thereby energizing this relay to cause its contacts to be drawn up. Assuming for purposes of illustration that station 11 is nonselected then it may be seen that the drawing up of the contact 38 completes a locking circuit for the relay 39 which may be traced from positive battery through the normally closed contacts 32-34, over the lead 37, through the now closed contacts 38, through the windings of the relay 39 to negative battery. It is to be recalled that energization of the relay 39 also closes the contacts 84 thereby completing the previously traced energizing circuit for the busy lamp 86 hence the attendants at the unoperated outlying stations are apprised of the fact that the system has certain stations which are in a selective condition in anticipation of the transmission of messages

through the system, but that this station is an unselected station and is not going to record these messages.

At the stations that are selected to receive the messages both the "on" lamp and the "busy" lamp 86 are illuminated, hence the attendants at these stations are informed of the fact that a message is forthcoming through the system and the station is going to record a message. It is of interest to note that at the nonoperated stations, the start switch 31 is disconnected from the source of positive battery due to the closure of the contact 38 and the failure of the relay 36 to be energized to close its contact 38. At all the selected stations including the initiating station, the start switch 31 is connected to the source of positive battery which circuit may be traced from positive battery through the normally closed contact pair 32-34 of the de-energized relay 33, through the now drawn up contact 88 of the relay 36 over a lead 89 to the lower terminus of the start switch 31.

Following transmission of the message it is desired that the system be restored to its unoperated condition preparatory to the transmission of subsequent messages to different arrangements of stations. The operator at the initiating station 10 will close his start switch 31 which as previously described with respect to the initiation of a call to the outlying station causes the transmission line contact 42 to open whereupon the relays 33 are operated at all of the outlying systems including those which were nonselected. Operation of the relay 33 causes the contact 32 to move from engagement with the contact 34 hence the holding circuits for the relays 39 and 36 are broken at all of the selected stations including the initiating station 10. Operation of relay 33 is also followed by an energization of the motor control circuit at all of the nonselected stations, hence it may be comprehended that all the motors at all the stations in the system are now in a running condition. The operator at the transmitting station then transmits a signal which is indicative of a carriage return function thereby effectuating a movement of a function lever 23 to open the contacts 62 at all of the outlying stations causing positive battery to be removed from the motor control relays 59 thereby permitting the contacts associated therewith to open and as a result all of the motors 27 at all of the stations are shut off. The system is now in condition for the setting up of another pattern of stations to receive messages.

It is to be understood that the above-described arrangements of circuits, components and elemental parts are simply illustrative of an application of the principles of the invention and that many other modifications and arrangements may be made without departing from the invention.

What is claimed is:

1. In a multistation communication system wherein each station is permanently connected to a signaling line and each station includes a normally de-energized apparatus, a control circuit for operating said apparatus, an electronic tube, first and second time delay charging circuits adapted to operate each tube, discharge means for rendering said charging circuits ineffective, an initiating relay circuit, selective means for energizing said initiating relay circuit to operate said control circuit to operate the apparatus at an initiating station, means for locking said apparatus control circuit in the operated condition, means operated by said selective means for rendering said discharge means ineffective and said first charging circuit effective to operate the tube, means operated by said tube for restoring said initiating relay circuit to the unoperated condition, means at all stations responsive to the operation of the selective means at any other station for rendering the associated discharge circuit ineffective and said second charging circuit effective to operate the associate tube, and means operated by the tube in response to actuation by said second charging circuit for operating the apparatus control circuit at that station.
2. In a multistation telegraph system wherein each sta-

tion is operably associated with a single signaling channel and each station includes a normally unoperated motor control circuit, an initiating relay circuit for operating said motor control circuit, an electronic tube, first and second time delay charging circuits adapted to operate each tube, discharge means for rendering said charging circuits ineffective, selective means for energizing said initiating relay circuit to operate said motor control circuit, means for locking said motor control circuit in the operated condition, means operated by said selective means for rendering said discharge means ineffective and said first charging circuit effective to operate the tube, means operated by said tube for restoring said initiating relay circuit to the unoperated condition, means at all stations responsive to the operation of the selective means at any other station for rendering the associated discharge circuit ineffective and said second time delay circuit effective to operate the associated tube, and means operated by said tube for operating the motor control circuit at that station.

3. In a telegraph system having a plurality of stations serially interconnected by means of a normally energized signaling line, a normally unoperated motor at each station, means at each station for operating said motor which comprises a line contact, a line relay energized by said energized signaling line, a tube, a charging circuit normally tending to fire said tube, a discharge circuit maintained by said line relay for precluding the charging circuit from firing the tube, a normally open start relay circuit adapted to operate said motor, selectively operable relay means for opening said line contact to de-energize said line relay whereupon said charging circuit fires the tube after a predetermined time delay, means actuated by the de-energization of the line relay and the selectively operable relay means for closing the start relay circuit for the motor, means operated by the start relay circuit for locking the motor in the running condition, and means operated by the firing of the tube for closing the line contact to restore the line relay to its initial condition whereby the start relay circuit is restored to the normal open condition.

4. In a telegraph system as defined in claim 2 which includes means operated by the firing of the tube for de-energizing said tube.

5. In a telegraph system, a line circuit, stations connected in series in said line circuit, a contact in the line circuit at each station, a normally unoperated motor at each station, circuit means at each station for initiating operation of the motor thereat and for opening the line contact thereat, means operated by the initiating means for locking the motor in the operative condition, an electronic tube at each station, first and second charging circuits associated with and adapted to operate each tube, said charging circuits having different periods of operation, means at each station for rendering the charging circuit thereat ineffective, means at the initiating station responsive to the opening of the line contact thereat for render-

ing the first charging circuit effective whereby the tube is rendered operative after a first period of time, means operated by the tube for rendering ineffective said initiating circuit means for said motor, means at all of the other stations operated by the opening of said line circuit for rendering said second charging circuits effective whereby said tubes thereat are rendered conductive after a second period of time, and means operated by the operation of the tubes at these other stations for rendering effective the initiating circuits for the motors thereat.

6. In a telegraph system as defined in claim 4 which includes means operated by de-energization of the initiating circuit at the initiating station for rendering the tube thereat nonconductive.

7. In a telegraph system as defined in claim 4 which includes means operated by initiating circuit at said other stations for locking the motor in the operative condition, and means operated by the initiating circuit at these other stations for rendering the tube nonconductive.

20 8. In a telegraph system having a plurality of stations permanently associated with a signaling line, each of said stations comprising a normally unoperated motor for driving the telegraph equipment thereat, a line contact at each station, a tube at each station, a first charging circuit adapted to operate said tube after a relatively long time duration, a second charging circuit adapted to operate said tube after a relatively short time duration, means at each station for precluding each charging circuit from operating the associated tube, an initiating circuit at each station for opening said line contact to render effective said first charging circuit to operate said tube after said relatively long time duration, relay circuit means actuated by said initiating means for operating the motor, means operated by the relay circuit means for locking the motor in operative condition, means operated by the firing of the tube for closing the line contact to restore the relay circuit means to the initial condition, means at each station responsive to the opening of the line contact at any other station for rendering ineffective said precluding means and rendering effective said second charging circuit to fire the tube thereat, and means operated by the firing of the tube at all but the initiating station for operating the relay circuit means thereat to operate and lock the motor in the operative condition.

45 9. In a telegraph system as defined in claim 8 wherein means at an initiating station are actuated by the firing of the tube thereat to restore the line contact, and means at all the outlying stations actuated by the reclosure of the line contact for restoring the tube and relay circuit means to the unoperated condition.
